RELEASING CLAMP

Stewart L. Moore, Jr., Baltimore, Md., assignor
to Locke Insulator Corporation, Baltimore, Md.,
a corporation of Maryland

Application November 7, 1928. Serial No. 317,856

4 Claims. (Cl. 248—31)

The invention relates to clamps for suspending the high tension conductors of transmission lines.

The principal object of the invention, generally stated, is to provide a clamp of such construction that while it will hold a conductor firmly under normal circumstances, it will release its grip upon the conductor and permit the latter to slide through in the event that an excessive strain occurs on the line at one side of the clamp.

It is well known that it is customary to support conductors by means of clamps at the lower ends of strings of insulators, such strings being suspended from steel towers or other equivalent supports. In the event that a greater strain comes upon the conductor on one side of the tower than on the other, the string of insulators will move out of their normal substantially vertical position, resulting in probable severe damage to the insulators and possible upsetting of the tower. This dangerous condition is particularly noticeable on lines where there is an extremely long span between successive towers. The excessive strain referred to may sometimes be the result of high winds but is generally caused by an accumulation of sleet or ice upon the conductor. An additional contingency is: breakage of the conductor. It is obvious that in the event of a break substantially the entire weight of the conductor throughout a span comes upon one string of insulators.

It is with the above facts in view that I have devised the present invention which has for a more specific object the provision of a clamp which will hold the conductor firmly under normal circumstances, or even under slightly abnormal circumstances, but which will automatically release in the event of breakage of the conductor or the occurrence of any other unusual and unequalized strain.

An important object of the invention is to provide a clamp for this purpose of such formation that it will be capable of regripping the conductor after the conductor has been released and has slid through a plurality of clamps at a series of towers until the strain has been substantially equalized.

Still another object of the invention is to provide a clamp embodying a resilient or spring clamping member positively forced into engagement with the conductor, it being a feature that the thickness or gauge of the material from which the spring clamping member is formed provides means whereby the degree of holding action may be regulated so as to permit or insure release of the clamping action upon the occurrence of a

certain definite predetermined pull or strain, this feature rendering it possible to make use of a single type and size of clamp, with a selectively usable movable and removable clamping member, upon different installations.

Another object is to provide a clamp having means whereby the relatively movable clamping member will be prevented from actual separation or disengagement from the main body or relatively fixed clamping member, dropping down and probable loss being thereby avoided.

An additional object is to provide a clamp of this character which will be simple and inexpensive to manufacture, easy to install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of the clamp in position upon a conductor.

Figure 2 is a vertical longitudinal section through the main body or relatively stationary member.

Figure 3 is an end elevation with the conductor in section, and

Figure 4 is a central vertical cross section, the view being taken on the line 4—4 of Figure 1.

Referring more particularly to the drawing I have shown the clamp as comprising a main body or relatively stationary member 1, a relatively movable clamping member 2, a suspension member 3 and a pivot bolt 4. Though it is not essential, the main body member 1 is here represented as of sheet metal construction and of elongated stirrup-like form. In other words this member may very well be U-shaped in vertical cross section, thus providing spaced sides 5 connected by a seat 6 which preferably conforms to the curvature of the conductor to be held. The ends of the seat portion are preferably flared or curved downwardly as at 7 to avoid contact of the edges with the conductor 8. It is also preferable that the sides 5 be formed with openings 9 which need not, however, have the specific shape disclosed.

The movable clamping member 2 is preferably of sheet metal construction and may be longitudinally bowed upwardly at its center as shown in Figure 1 for cooperation with a cam extension 10, or its equivalent, formed on or carried

by the suspension member 3. It is preferable that the ends of the member 2 curve upwardly away from the conductor 8 to prevent edge contact therewith. In order to prevent any longitudinal shifting of the member 2 with respect to 5 the main member 1, the former is shown as having lateral projections 11 fitting somewhat loosely within the openings 9 though it is apparent that some other detailed construction could be used instead. A very convenient structure is 10 that the entire device be formed of sheet metal though I do not care to be limited in this respect as the invention is of greater scope. It is very likely that if the body member or supporting stirrup be formed of sheet metal the clamping member may be rigid. The point is that 15 there is a reaction between the body or stirrup and the clamping member and by making one or the other yieldable to a limited extent certain advantages will ensue.

20 The bolt 4 above referred to provides an extremely simple means for connecting the suspension member 3 with the body member 1, this bolt or pin simply passing through a hole 12 in the suspension member and seating within the 25 upper ends of the openings 9. In the present instance this element 4 is shown as a pin equipped with a cotter 13 to prevent withdrawal though it is quite apparent that a bolt and nut may be used if preferred. Aside from the provision of 30 the cam projection 10 the specific construction of the suspension member 3 is of little importance though it is shown as of clevis formation and provided in its upper end with holes 14 to permit connection, by a bolt or the like, with a 35 suspension element attached directly, or through some intermediate means, to the lower end of a string of insulators, not shown.

In effecting installation, it is clear that the 40 main member 1 is engaged beneath the conductor 8, subsequently to which the relatively movable member 2 is inserted within it so as to lie on top of the conductor, it being easily possible to cant or tilt the member 2 to bring the projections 11 into the openings 9. Regardless of 45 whether the suspension member 3 is connected with the string of insulators prior or subsequent to its connection with the clamp, it should be plain that to complete the assembly the suspension member 3 should be inclined from the vertical 50 so that the cam projection 10 will not engage upon the member 2. The hole 12 must be lined up with the openings 9 so that the pin or bolt 4 may be inserted and cottered. When 55 weight is then permitted to come upon the assembly, the suspension member 3 will assume a vertical position with the cam projection 10 contacting firmly with and depressing the center of the clamping member 2 so that this member will grip the conductor firmly. This action will be 60 maintained or will continue while the member 3 is in normal or substantially vertical position, as it will be when there is no difference in strain on the conductor at either side of the clamp. In the event of breaking of the conductor or some 65 other unusual occurrence producing an unusual pull at one side of the conductor or the other, the string of insulators, not shown, and the suspension member 3 would swing out of vertical position whereupon the cam projection 10 will 70 either ride off from the clamping member 2 or reach such a position that the pressure upon the member 2 will be relieved if not entirely eliminated, this depending upon the degree of swinging movement. When the pressure upon the

member 2 is thus decreased the conductor may slip through the clamp. This slippage would occur perhaps through a series of clamps along the line until the excessive strain is relieved. Upon return of the insulator string and member 3 to normal or substantially vertical position the clamp will regrip the conductor without necessitating a local manual operation.

80 A very important feature is the making of the member 2 from sheet material. Clearly, if a thinner material is used the clamping action will be less and the clamp will release at a lighter pull than would be the case if the thickness of the member 2 were to be increased. By this one means it therefore becomes possible to use 85 the clamp in different installations as it is merely necessary to have the interchangeable members 90 2 of different gauge or thickness.

95 The shape of the cam extension 10 may be varied if found advisable, depending upon the inclination of the insulator string at which release is desired. No elaborate data is given as to the curvature or other shape as there are so many possibilities and as this is a detail which may well be worked out by actual experimentation.

100 From the foregoing description and a study of the drawing it will be seen that I have provided a very simple, inexpensive and easily applied clamp which will, nevertheless, be extremely efficient in action. On account of the fewness of the parts actual manufacture becomes an easy proposition and assembly is greatly facilitated. It is thought that the construction, 105 operation and advantages will be readily apparent to one skilled in the art without further explanation.

110 While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no 115 departure from the spirit of the invention or the scope of the claims hereunto appended.

120 Having thus described the invention, I claim:

1. A clamp of the character described comprising an elongated stirrup-like main member 125 having upstanding sides, a relatively movable member located between the sides of said first named member and provided with lugs at its sides, and a suspension member pivoted between the sides of said first named member and having 130 a cam projection normally engaging the second named member for effecting a clamping action on a conductor, said sides having openings receiving said lugs, and the pivotal connection between the first named member and the suspension member 135 being engaged within said openings.

2. A clamp of the character described comprising a relatively stationary clamping member 140 disposable beneath a conductor, a relatively movable clamping member formed as a leaf spring disposable above the conductor within the confines of said relatively stationary clamping member, means for preventing relative longitudinal movement of said members comprising lugs on the movable member engaged within the lower 145 ends of the openings in the sides of said stationary member, and suspension means having cam means thereon cooperating with one of said members for forcing said members into clamping relation to the conductor, the suspension means 150

including a bolt engaged within the upper ends of said openings and reacting against the upper edges thereof.

3. A clamp for supporting a conductor, comprising an elongated channel shaped body having the intermediate portion of its sides upwardly extended and formed with vertically elongated openings with rounded upper ends, a longitudinally bowed member located within said channel shaped member and having laterally projecting lugs received within the lower portions of said openings, a suspension member provided at its lower end with a cam portion reacting against the center of said clamping member, and a pivot for said suspension member extending through said openings and reacting against the curved upper ends thereof.

4. A clamp for supporting a conductor, comprising an elongated channel shaped body having the intermediate portion of its sides upwardly extended and formed with vertically elongated openings with rounded upper ends, a longitudinally bowed member located within said channel shaped member and having laterally projecting lugs received within the lower portions of said openings, a suspension member provided at its lower end with a cam portion reacting against the center of said clamping member, and a pivot for said suspension member extending through said openings and reacting against the curved upper ends thereof, said channel shaped member being of one piece sheet metal construction.
